2,100,185

APPARATUS FOR THE MOVEMENT OF VISCOUS MATERIALS

Gunnar C. Engstrand, Matawan, N. J., assignor to Simon Marmorek, New York, N. Y.

Application November 6, 1936, Serial No. 109,465

2 Claims. (Cl. 103—267)

My invention relates to an apparatus and method whereby viscous and semi-fluid tars and sludges may be pumped through a transmission line, and it is especially adapted for the removal of oil residues from the storage tanks of oil refineries, at the bottom of which, in the length of time, heavy and extremely viscous sludge deposits collect in such considerable quantities that they seriously encroach upon the storage space 5 of said tanks.

Also as such extremely viscous and semi-fluid sludges usually become mixed with rust scale and carbon deposits, the resulting mixture is so plastic and inert that even a powerful pump suction 15 fails to move the material through a transmission line, and when such tanks have to be cleaned, the usual procedure is to dip up the unpumpable matter in buckets and dump cars in which it is transported as a total economic waste and dumped at a place especially set aside 20 for such purpose.

I am well aware of several special novel pumping methods for the handling of heavy viscous oil sludges, but as all such methods invariably 25 employ reduced intake openings, such systems cannot be successfully used for the pumping of aforesaid inert materials, inasmuch as even the most powerful vacua fail to suck up a sufficient 30 quantity of such extremely viscous material through such relatively small intake openings.

I have, however, discovered that it is possible to pump much material at a satisfactory rate 35 by means of a specially designed high vacuum steam jet pump. My special sludge pump comprises a pump body having the narrow throat passage of the conventional high vacuum steam jet pump into which a conventional annular steam jet nozzle discharges.

At the intake end of the pump I also provide 40 an additional large diameter steam nozzle also of the annular design, which nozzle discharges into and through the first mentioned annular steam jet nozzle. It is to be noted that the high vacuum which is created by the narrow throated 45 jet pump will suck the material only through the relatively large intake nozzle piece as the material thereafter is quickly blown through the inner nozzle passage and into the narrow throat discharge of the jet pump.

I have found that for extremely heavy and 50 viscous sludges the pumping rate of a steam jet pump becomes from 300 to 400 per cent greater when the additional intake feed nozzle piece is used.

I have also found that where more fluid sludges

are encountered, the most economical pumping 5 may be attained by the solitary use of the discharge jet nozzle only. I, therefore, prefer to provide each of the steam nozzles with an individual control valve so that a perfect regulation of the steam supply may at all times easily be effected.

I also prefer to so construct my pumping apparatus that each of the nozzle pieces may be individually adjusted and securely locked in 10 place.

It is further to be noted that the aforesaid plastic and viscous mixtures in passing through the two steam jets of my preferred apparatus 15 are returned into their originally oily condition and that rust scales, carbon deposits, etc., are so thoroughly pulverized and mixed with the oil that the material can now be pumped by conventional pumping means and even burned in the conventional burners under the boilers. 20

In the drawing:

Figure 1 is a longitudinal cross section of my special duplex jet sludge pump and shows the preferred manner of construction.

Figure 2 is a cross section through the narrow throat portion of the pump and shows the reinforced rib construction thereof.

In the drawing where like reference characters designate corresponding parts, 1 denotes the pump body which I preferably make of cast 30 metal.

As seen on the drawing, the pump body comprises the relatively narrow throat portion 3, the enlarged socket discharge end 2, which is preferably threaded to receive standard pipe and 35 hose fittings, and the enlarged socket end 4 which is provided with the running thread 5 and into which end the two nozzle pieces 6 and 7 are screwed.

The inner nozzle piece 6 is provided with the 40 lock ring 8 and the nozzle piece as well as the lock ring are provided with two diametrically opposed recesses 9 to allow for accurate key adjustment.

It is to be noted that the nozzle piece 6 together with the tapered portion of the pump body form the steam jacket 10 which is provided with an individual steam inlet 11 controlled by the steam valve 12. The taper end 13 of the nozzle piece 6 forms together with the inside tapered 50 wall portion of the pump body, the annular narrow steam jet opening 14 through which the high pressure steam escapes from the jacket.

The outer nozzle piece 7 is also screwed into the end portion 4 of the pump body and is so lo- 55

cated that a narrow annular steam jet opening 15 is formed between the outer and the inner nozzle piece as shown in the drawing. The steam jacket 16 is also provided with an individual steam 5 inlet 17 and a separate control valve 18.

The nozzle piece 7 is also provided with recesses 9 to allow for easy key adjustment and this nozzle piece is effectively locked in place by the coupling piece 19, the one end of which 10 is provided with a screw thread to fit over the threaded shank of the nozzle piece 7 while the other end is provided with a screw thread accommodating standard pipe and hose fittings.

The relatively slender throat portion 3 of the 15 pump body is shown provided with proper reinforcing ribs 20.

The action of the pump is as follows:

The two nozzle pieces of the pump having been locked in their proper positions so as to have 20 proper steam jet clearance, say around one-thirty-second of an inch, the control valves 12 and 18 are opened and the high pressure steam is allowed to enter the steam jackets 10 and 16 whereupon the high pressure steam will rush 25 into the pump through the two annular steam nozzles 14 and 15 with a velocity of nearly 3000 feet per second.

Although it is believed that the proportions 30 may be changed from that shown on the drawing, I have found it possible to create a vacuum much in excess of twenty inches inside a four inch transmission line when the pump throat passage as well as the inner nozzle passage have a diameter of two inches and the diameter of 35 the outer nozzle passage is kept at three inches.

It is readily understood that quite an amount 40 of viscous material will be pulled through such a large intake opening when propelled by such a high vacuum and it is also readily seen that even the most viscous material will be fed into the second steam jet nozzle at a brisk rate as the intake steam jet pulls it along and discharges it therein.

It is to be noted that the throat passage of the pump is made relatively narrow in order for a high vacuum to develop as experience has taught me that a relatively narrow throat opening is required for the creation of a high vacuum. 5

It is also to be noted in this connection that the viscous material will not set up an excessive nozzle friction in passing through the large outer nozzle opening and also that its passage through the inner nozzle opening will proceed practically 10 frictionless as the material is swept along its surface by the outer steam jet.

I wish also to point out that an interaction between the two steam jets automatically takes place in my steam jet pump, the inner nozzle 15 acting mainly as a pressure discharge nozzle while the outer nozzle acts solely as a vacuum intake nozzle.

I do not wish to be understood as limiting myself to the apparatus shown, as it is evident that 20 modifications and alterations may be made in my device without departing from the spirit and scope of my invention.

What I claim is:

1. A steam jet pump comprising, in combination, 25 a narrow throat piece, an inner annular steam jet nozzle discharging therethrough, a restricted passage through said nozzle, an outer annular steam jet nozzle discharging through the passage of the inner steam jet nozzle, a passage through the outer nozzle, the outer nozzle 30 passage having a substantial larger cross section than the passage of the inner one.

2. In a steam jet pump, a throat body, a plurality of concentric annular steam jet nozzles discharging into and through the throat body and individual and independent means for clearance adjustment for each of the steam jet nozzles, a central passage through each of the nozzles, the diameter of an inner nozzle being substantially 35 smaller than that of an outer one. 40
